UNITED STATES PATENT OFFICE.

CHARLES HENRY BULL, OF CHICAGO, ILLINOIS.

CAR-SEAL.

1,003,980.

Specification of Letters Patent. Patented Sept. 26, 1911.

Application filed March 20, 1909. Serial No. 484,655.

To all whom it may concern:

Be it known that I, CHARLES HENRY BULL, a citizen of the United States, residing at Chicago, in the county of Cook and State of Illinois, have invented certain new and useful Improvements in Car-Seals, of which the following is a full, clear, and exact description, such as will enable others skilled in the art to which it appertains to make and use the same.

10 This invention relates to sealing devices and more particularly to devices of this character adapted to be used for sealing doors of freight cars and the like.

15 One of the objects is to provide a device of this character which may be quickly attached in position and positively locked to prevent its being removed therefrom.

20 Another object is to provide a device which will be simple in its construction and cheap to manufacture, and which will be highly efficient in use.

25 Other objects will be in part obvious and in part pointed out hereinafter.

30 The invention accordingly consists in the features of construction, combinations of elements and arrangement of parts which will be exemplified in the construction herein-after set forth, and the scope of the application of which will be indicated in the following claims.

35 In the accompanying drawings, wherein is shown one of various possible embodiments of the invention, Figure 1 represents the device as applied to the fastening of a door; Fig. 2 is a plan view of the device before having a sleeve formed thereon; Fig. 3 is a sectional view taken on the line 3—3 of Fig. 2; Fig. 4 is a longitudinal sectional view of 40 the device showing the looping member locked within the sleeve; and Fig. 5 is a sectional view taken on the line 5—5 of Fig. 4.

45 Similar reference numerals refer to similar parts throughout the several views.

50 Referring now to Fig. 2 of the drawing, 1 indicates a looping portion having one of its ends united to a sleeve portion 2, the width of the latter being at least double that of the former, whereby it may be folded upon itself to form a sleeve within which the free end of the looping portion may be inserted in the manner hereinafter described. As shown in this figure the portions 1 and 2, which are preferably formed from sheet metal, are integral with one another, being preferably formed from a single piece of metal, but it

will, of course, be understood that they may be made separate from one another and united in any suitable manner although the integral construction possesses many advantages. The sleeve portion is provided with suitable retaining means comprising, in the embodiment shown tongues 3 and 4 preferably struck-up from the metal of which the portion is composed. The tongue 3 which is the more remotely positioned from the looping portion 2 is bent back to extend beneath the tongue 4 with the under side of which it is held in contact owing to the resiliency of the metal as clearly shown in Fig. 3. In the preferred form, a plurality of pairs of tongues are provided in alignment with one another and with the looping member 1 as shown in Fig. 2. Intermediate the ends of the looping member 1 are pairs of perforations 5 and 6 spaced from one another to form a locking strip 7 adapted to interlock with the locking tongues as hereinafter described. Preferably, the looping member is provided with a plurality of these strips, as shown in Fig. 2, any one of which is adapted to interlock with any one of the pairs of locking tongues formed in the sleeve portion.

55 After the parts have been formed as above described, the sleeve portion 2 is bent or folded upon itself to form a sleeve 8, with the locking tongues lying within the opening thereof, and is retained in its folded condition in any suitable manner, as, for example, by applying solder to the free edge thereof as indicated at 9 in Fig. 5.

60 The method of use of the device, which should be largely obvious from the above description, is as follows:—When it is desired to apply the seal, the hasp 10 which, by way of illustration, is shown mounted upon a door 11, is first placed in locking position with its associated staple 12, which is shown secured to the door frame 13, extending through the opening 14. The looping member 1 is then inserted through the staple and hasp and bent to form a loop 15 and its free end is inserted within the opening in the sleeve 8 through which it may pass freely, the strips 7 passing over the tongues 4 which offer no obstruction to movement in this direction. The looping member is then moved in the opposite direction with respect to the sleeve, which movement will cause one of the locking strips 7 105 to pass beneath one of the overlapping

tongues 4, as indicated in Fig. 4, the co-acting tongue 3, on account of its resiliency, springing back into its normal position to effectually lock the strip in position and prevent the removal of the looping member from the sleeve. After the parts are thus positioned, a suitable stamping device is applied to the sleeve to force the parts into more intimate contact with one another in order to more effectually lock the parts in their positions and impress a distinctive character or letters in the metal.

By employing a plurality of locking strips as well as a plurality of pairs of locking tongues, it will be seen that the looping member may be so positioned with respect to the sleeve that loops of various sizes may be formed to accommodate staples or other similar devices of various sizes, due to the fact that each locking strip is adapted to co-act with each pair of tongues.

It will be seen from the above description that this device may be quickly attached and effectually locked in its operative position, and that it will be impossible to remove the same after it has been thus locked without destroying the seal. If desired, after the seal has been affixed, as shown in Fig. 1, the portion of the locking member which extends beyond the outer end of the sleeve may be cut off as shown in said figure. When the car has reached its destination, it is merely necessary to cut the loop in order to release the hasp to enable the door to be opened.

While the seal is shown and described as being applied to the latch of a door, it will, of course, be understood that it may be employed in connection with other locking or fastening devices when it is desired to prevent access by unauthorized persons.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense. It is also to be understood that the language used in the following claims is intended to cover all of the generic and specific features of the invention herein described and all statements of the scope of the invention, which, as a matter of language, might be said to fall therebetween.

Having described my invention, what I claim as new and desire to secure by Letters Patent is:

60 1. In a device of the class described, in combination, a sleeve, a looping member integrally united thereto and adapted to be bent into a loop and inserted within said sleeve, said sleeve having means for retaining said member therein in any one of a

plurality of positions whereby loops of different sizes may be formed thereby.

2. In a device of the class described, in combination, a sleeve provided with a plurality of retaining means, and a looping member integrally united to said sleeve and adapted to be bent into a loop and inserted within said sleeve, said member being provided with means adapted to engage any one of said retaining means to retain said member in any one of a plurality of positions. 70

3. In a device of the class described, in combination, a sleeve provided with a plurality of retaining means, and a looping member united to said sleeve and adapted to be bent into a loop and inserted within said sleeve, said member being provided with a plurality of means any one of which is adapted to engage any one of said retaining means to retain said member in any one of a plurality of positions. 75

4. A seal comprising in a single piece of sheet metal, a sleeve open at both ends; a plurality of pairs of oppositely disposed coacting tongues struck up from the metal of the seal within the sleeve, the free end of one of said tongues overlapping the free end of the other; and a looping member adapted to be bent into a loop and passed through said sleeve, said looping member being provided with locking members adapted to pass between the ends of any one of said pairs of overlapping tongues to retain the looping member against further movement in the sleeve. 80 90

5. In a device of the class described, the combination of a sleeve open at both ends and provided with a pair of retaining members struck up from the material of which the sleeve is composed, one of said members being bent back into engagement with the other of said members; and a looping member united to said sleeve and adapted to be bent into a loop and inserted through the sleeve, said member being provided with a series of latching perforations whereby it is adapted to engage the retaining members in adjustable relation. 105

6. A seal comprising in a single piece of sheet metal, a sleeve; a plurality of pairs of oppositely disposed coacting tongues formed within the sleeve, said pairs of tongues being aligned longitudinally with respect to said sleeve, the free end of one of said tongues overlapping the free end of the other; and a looping member adapted to be bent into a loop and passed through said sleeve, said looping member being provided with a locking member adapted to pass between the overlapping ends of any one of said pairs of tongues to interlock therewith to retain said looping member in position. 110 115 120

7. In a device of the class described, in combination, a sleeve provided with a plu- 130

rality of pairs of oppositely disposed coacting tongues, said pairs of tongues being alined longitudinally with respect to said sleeve, the free end of one of said tongues overlapping the free end of the other, and a looping member united to said sleeve and adapted to be bent into a loop and inserted within said sleeve, said looping member being provided with a plurality of alined locking strips, any one of which is adapted to pass between the overlapping ends of any one of said pairs of tongues to interlock therewith, to retain said member in position.

8. A seal comprising in a single piece of sheet metal, a relatively narrow looping portion having a series of latching perforations; an enlarged portion at one extremity of the looping portion, said enlarged portion being folded about itself to form a sleeve closed at the sides and open at the ends to permit passage of the looping portion; and a pair of oppositely disposed overlapping tongues struck up from the metal of the seal within the sleeve and concealed by the

successive folds thereof, the said tongues being adapted to enter the perforations of the looping portion to retain the latter within the sleeve.

9. A seal comprising in a single piece of sheet metal, a looping portion having a series of perforations; an enlarged portion at one extremity of the looping portion folded about itself to form a sleeve closed at the sides and open at the ends to permit the passage of the looping portion; and a plurality of pairs of overlapping tongues struck up from the metal of the seal within the sleeve, the tongues of each pair projecting toward each other and each pair of tongues being adapted individually to enter perforations in the looping portion.

In testimony whereof I affix my signature, in the presence of two witnesses.

CHARLES HENRY BULL.
